UNITED STATES PATENT OFFICE.

FREEBORN F. RAYMOND, 2d, OF NEWTON, MASSACHUSETTS, ASSIGNOR, BY MESNE ASSIGNMENTS, TO THE UNITED SHOE MACHINERY COMPANY, OF NEW JERSEY.

NAILING-MACHINE.

SPECIFICATION forming part of Letters Patent No. 654,762, dated July 31, 1900.

Application filed December 17, 1889. Serial No. 384,114. (No model.)

To all whom it may concern:

Be it known that I, FREEBORN F. RAYMOND, 2d, a citizen of the United States, and a resident of Newton, in the county of Middlesex 5 and State of Massachusetts, have invented a new and useful Improvement in Nailing-Machines, of which the following is a full, clear, and exact description, reference being had to the accompanying drawings, forming a part 10 of this specification, in explaining its nature.

The invention relates to a machine for making nails from wire having a rolled point, for transferring the nails to the nail-driving device to the nail-driving mechanism, and to 15 various details of construction and organization, all of which will hereinafter be more particularly set forth.

In the drawings the invention is illustrated as embodied in a machine for driving nails 20 singly into the soles of boots and shoes.

Referring to the drawings, Figure 1 is a view in side elevation of a machine having the features of my invention. Fig. 2 is a view in vertical section taken through the die-rolls. 25 Fig. 3 is a view in side elevation of the head of the machine enlarged. Fig. 4 is a detail view to illustrate a portion of the mechanism for operating boot or shoe feed, to which reference is hereinafter made. Fig. 5 is a detail 30 view in section illustrating the boot and shoe feed. Fig. 6 is a view illustrating a portion of the wire-feed. Fig. 7 is a detail view representing the position of the parts in the act of driving the nail. Fig. 8 is a 35 view representing the dies as having a point-drawing section and also a feeding-section, to which reference will hereinafter be made. Fig. 9 is a view in plan of a portion of the reverse-feed roll. Fig. 10 is a view of the 40 same, with the exception that a feed-block for imparting a shorter vertical feed has been substituted for the one represented in Fig. 9; and Fig. 11 is a view in section of a portion of the feed-roll, showing the feed-block of Fig. 45 10 thereon.

A is the standard of the machine. Upon it is mounted the frame a, carrying the nail making and driving devices.

B is the driving-shaft of the machine. It 50 carries the driving-pulley b, upon which is arranged one section b' of a clutch. There

is arranged upon the shaft B to engage this member of the clutch the member b², which is formed upon or attached to the pinion b³. This pinion, with the member b² of the clutch, 55 is given a movement upon the shaft to engage and disengage the section b' of the clutch by means of the lever b⁴, pivoted at b⁵ and connected by the rod b⁶ with an operating-treadle b⁷. The upper end of the lever b⁴ is 60 forked and connected with the pinion b³ and member b² of the clutch by pins b⁸, which enter a groove b⁹ in a collar attached to the pinion or integral therewith. A spring b¹⁰, attached to the treadle at one end and to the 65 frame of the machine, serves to lift the treadle and to move the pinion and the member b² of the clutch from engagement with the member b' and to hold the said member disengaged.

The shaft B is connected with the roll-shaft C by means of the gear c, and the shaft C is connected with the other or second roll-shaft C' by a gear c', which meshes with a gear upon the shaft C'. At the forward end of the shafts C C' are the die-rolls D D'. Each die-roll carries three sections d d' d² of three pointing-dies. The die-roll D also carries a cut-off d³ for each die, operated by an operating-bar d⁴, contained in a central hole in the shaft C and 80 having its end wedge-shaped or tapered to act against the inner ends of the cut-off bars which enter the hole in the shaft. Motion lengthwise the shaft C is given the cut-off bar by means of the slide d⁵ upon the shaft C, 85 connected with the bar by means of a pin passing through a slot in the shaft, the lever d⁶, pivoted at d⁷, and the cam projection d⁸ upon the cam-disk d⁹ at the front end of the shaft B, and the retracting-spring d¹⁰. The 90 roll D' has a presser-bar d¹¹ for each die forced outward by a spring. The cam-shaft B makes three revolutions for every single revolution of the die-rolls D D'. The dies are shaped to not only form the point of the 95 nail in the wire, but also to feed the wire a limited distance, the die-surfaces being roughened or corrugated to accomplish this purpose, and in Fig. 8 I represent the dies as thus formed, the sections e of the dies representing the pointing-sections and the sections e' the feeding-sections. Of course the pointing-

sections feed the wire equally with the remaining sections of the dies, but they act additionally to roll the point of the nail in the wire as they feed. If it is desired to obtain a shorter nail than is thus pointed and fed from the wire after a pointed section has been removed or cut off by the operation of a cut-off and the point formed upon its end—that is, after the pointing-dies have left it—the rotary feed-blocks $f'f'$, of any desired width mounted upon the rolls $F'F'$, are brought into contact with the wire to lift or draw back the same any desired extent, so that upon the coming together of the next set of pointing-dies they close such distance from the end of the previously-pointed wire, as may be desired, which distance is regulated by the width of the feed-blocks $f'f'$. These blocks have corrugated surfaces and are adjustably secured to the rolls $F'F'$. (See Figs. 9, 10, and 11.) Each of the rolls $F'F'$ is represented as having three of these blocks. This is because the rolls are rotated at the same speed as the die-rolls $D'D'$, and the roll F is supported upon a shaft f^2 , and the roll F' upon the shaft f^3 . These shafts have bearings in the frame of the machine and are connected by the gears f^4f^5 , respectively, with gears f^6f^7 upon the shafts $C'C'$, these gears f^6f^7 connecting the two shafts $C'C'$ together at their forward ends, said shafts $C'C'$, as above stated, being connected at their rear ends by the gear c' on shaft C' meshing with a corresponding gear on shaft C , said gears f^6f^7 also meshing with the gears f^4f^5 , and this connection causes, of course, the feed-block rolls $F'F'$ to be rotated in the direction opposite to that of the die-rolls $D'D'$.

The devices for feeding the wire backward are represented in the form of blocks having preferably roughened surfaces and attached opposite to each other to rolls adapted to be turned backward. These blocks during the forward or usual feed of the wire separate from each other to permit the movement of the wire. They are closed upon the wire and moved backward when the wire is released by the usual feeding rolls or devices, and the extent of the said backward or reverse feed is varied by varying the length of the working faces of the blocks. If it should be desired to have but a short backward feed, the length of the working surfaces is relatively short. If it is desired to increase the extent of their backward movement, their length is increased. In any event they operate to provide a reverse feed which is shorter than the feed produced by the dies and usual feeding devices. The feed-block is held to the roll by screws, which permit it to be detachable, and the recesses are of a length to receive the longest feed-block, and thus provide for any lesser length desired.

The nail as it is pointed and severed is delivered from the dies to the transerrer G . This is mounted upon a plate g , having a throat g' at its forward end, and it has a hole

g^2 for the reception of the nail. The transerrer is at the end of a bar g^3 , which is by a link g^4 connected with the lower end g^5 of a lever g^6 . This lever is pivoted at g^7 and connected at its upper end g^8 with the cylinder-cam g^9 on the shaft B . The cam moves the transerrer from a position which brings its hole g^2 in line with the end of the wire which is to be fed therein and severed to a position over the throat-hole g' and under the driver H . (See Fig. 7.) The driver H is secured to a driver-bar h , carried in a housing h' , and the driver and bar are reciprocated at the proper interval of time by the lever h^2 , connected by a link h^3 with the upper end of the driver-bar, pivoted at h^4 , and connected by a link h^5 with a slide h^6 , having a cam-pin h^7 , which enters a cam-groove h^8 in the cam-disk h^9 on the shaft B . Beneath the throat-plate g is arranged a stud M , secured to the frame of the machine and having a hole m in continuation of the throat g' in the plate g and through which the nails are driven. This stud also furnishes a bearing for a feed-roll N and its operating-gear n and also for the free or loose roll n' . The feed-roll N is back of the passage m in the stud and has a roughened or corrugated surface. The loose roll n' is in front of the said hole m . There is arranged upon the feed-roll N a guiding-flange n^2 , against which the edge of the boot or shoe sole is held in contact during the nailing operation. This is preferably formed at the front of a sleeve n^3 , adjustable lengthwise the feed-roll N by means of a screw-thread connection between the two, and it is locked in any desired position by means of a set-screw n^4 . The feed-roll is positively rotated by means of the gear n^5 upon the shaft n^6 , which meshes with the gear n , and the gear n^5 and its shaft n^6 are rotated by means of a ratchet-wheel n^7 upon said shaft n^6 , the feed-pawl n^8 at the lower end of the lever n^9 pivoted at n^{10} and connected at its upper end by a cam-pin n^{11} with a cam-groove n^{12} in the cam-disk h^9 on the cam-shaft B . The cam, of course, imparts the feed movement to the feed-roll immediately after the driving of the nail, but before another nail is brought into position by the transerrer to be driven. A detent-pawl n^{13} engages the teeth of the ratchet-wheel n^7 and holds it during the reverse movement of the feed-pawl n^8 .

The boot or shoe is represented as supported during the nailing operation by a horn O , having the curved end o , which may have at its upper end a clenching-cup or, preferably, a grooved antifriction-roll o^2 , (see Fig. 7,) held in a pocket in the end of the horn and supported not only by its holding-shaft, but by the horn bearing upon its under side. This horn O is pivoted to swing horizontally at o^3 to a bracket o^4 , extending from the frame A , and it is attached to a rod o^5 , having a vertical movement and extending to a lever o^6 , which is pivoted at o^7 and carries at one end a heavy counterbalance and blow-absorbing

metal block o^8 and at the other end a treadle end o^9 . (See Fig. 1.) The wire is fed from a reel P , conveniently located through suitable guides to the drawing-rolls.

5 The operation of the machine is as follows: The boot or shoe is placed upon the horn and the horn lifted by means of the treadle o^9 to bring the upper surface of the sole in contact with the feed-roll, the sole edge being held in 10 contact with the edge-guide. The operator then starts the machine by depressing the lever b^7 , and this causes the dies to roll points in the wire and the cut-offs to be operated to sever the pointed ends and the reverse feed 15 to be operated to vary the length of the nails and the nails to be transferred by the trans-ferrer in successive order and driven from the trans-ferrer by the driver through the throat into the sole. The machine is so timed that 20 after a pointed nail has been delivered to the trans-ferrer the feeding of the wire ceases while the trans-ferrer moves the nail forward to a position under the driver. The driver is immediately reciprocated to drive the nail 25 from the trans-ferrer into the sole of the boot or shoe. The trans-ferrer is immediately returned, the feed-rolls caused to feed the shoe any desired distance, and the pointed end of the wire fed into the nail-receiving hole of the 30 trans-ferrer and then severed.

It will be seen that the horn holds the shoe with the sole in contact with the feed-roll; also, that where the horn is provided with a roll at its point, as shown in Fig. 7, the sole is 35 held between two rolls, one of which is positively driven and one is not. It will also be seen that the nail is driven between the upper roll, which is positively driven to feed the work and bears on the outside of the stock, 40 and a second roll that is free to rotate and which simply acts as a bearing-roll and not as a feed-roll. It will further be seen that by placing a teat or extension upon the stud in line with the hole therein the boot or shoe may 45 be channel-nailed—that is, the teat would extend into the channel and guide the placing and driving of the nails therein. It will further be seen that by changing the shape of the upper end of the horn the machine can be 50 used for driving slugs into the top lift of a boot or shoe heel.

Of course it will be understood that the drawing-dies can be modified to produce any desired form of point and that they can be 55 used upon wires of all section, either square, round, or rectangular, and that the reverse feed-blocks f^f' need not be used if not required, or if it is desired to make short nails or slugs that they may be of any desired 60 width to reverse the feed of the wire. It will be seen that these feed-blocks act when used after the trans-ferrer has received its nail and starts forward and before the next set of dies in order close upon the wire.

65 In some instances it will be desirable to make a long nail instead of a short nail, in which case the pull or draw back feed will

not be used and the longer nail will be obtained by the employment of dies such as are represented in Fig. 8—that is, dies having 70 point-forming sections and also a feeding-section.

Having thus fully described my invention, I claim and desire to secure by Letters Patent of the United States—

1. In a nailing-machine, the combination with a stud or block having a throat through which the nails are driven into the work, a work-support, a feed-roll on one side of said throat carried by said block, means for positively driving said feed-roll, and a freely-rotatable bearing-roll carried by said block on the other side of the throat.

2. In a nailing-machine, the combination with a block or stud having a throat through 85 which the fastenings are driven into the work, of a feed-roll mounted on said block or stud, said feed-roll having a threaded section, and an edge guide having a threaded sleeve mounted on said threaded section.

3. In a nailing-machine, the combination with a block or stud having a throat through which the fastenings are driven into the work, of a feed-roll mounted on said block or stud, said feed-roll having a threaded section, an 95 edge guide having a threaded sleeve mounted on said threaded section, and means for locking said edge guide onto said feed-roll.

4. In a nailing-machine, the combination with a block or stud having a throat through 100 which the fastenings are driven into the work, of a feed-roll mounted on said block or stud, and an edge guide carried by said feed-roll and detachable therefrom.

5. In a nailing-machine, the combination 105 with a block or stud having a throat through which the fastenings are driven into the work, of a feed-roll mounted on said block or stud, and an edge guide carried by said feed-roll and adjustable thereon.

6. In a nailing-machine, the combination with a block or stud having a throat through which the fastenings are driven into the work, of a feed-roll adjustably mounted on said block or stud, an edge guide carried by said 115 feed-roll and adjustable thereon, and means for locking said edge guide in its adjusted positions.

7. In a nail making or driving machine, the combination with rotary dies having a point-forming section and a wire-feeding section, of a reversely-acting wire-feed to draw the wire back any desired extent after it has been pointed and fed by the rotary dies.

8. In a nail making or driving machine, the combination with rotary dies having a point-forming section and a wire-feeding section, of a reversely-acting wire-feed to draw the wire back any desired extent after it has been pointed and fed by the rotary dies, and a cut-off to act upon the wire and produce a nail of the requisite length after it has been drawn back the desired extent by the reverse feed.

9. In a nail making or driving machine, the

combination with pointing-dies, of a wire-feed to move the wire forward, a secondary wire-feed to move the wire in a reverse direction, and a cut-off to sever the pointed wire 5 after the action of the reverse feed.

10. In a nail making or driving machine, the combination with the die-rolls D, D', having one or more pairs of wire pointing and feeding die-sections, a cut-off for each set of 15 dies, and the reverse-feed rolls F, F' rotated in an opposite direction from the direction of rotation of said die-rolls D, D', said rolls F, F' having a pair of feed-blocks for each pair of dies on said die-rolls.

11. In a nail making or driving machine, the combination with the die-rolls D, D', of

one or more sets of pointing and feeding dies mounted thereon, of the reverse-feed rolls F, F' mounted on the shafts f^2, f^3 , the feed-blocks f, f' , on said rolls, and the gears f^4, f^5, f^6 and 20 f^7 connecting the shafts of said die-rolls with the said shafts f^2, f^3 .

12. In a nail making and driving machine, the combination with the wire pointing and feeding dies, of a reverse wire-feed, a cut-off, 25 a nail-transferrer, a nail-throat, and a nail-driver.

FREEBORN F. RAYMOND, 2D.
